UNITED STATES PATENT OFFICE.

HERBERT A. FINNEY, OF CRUM LYNNE, PENNSYLVANIA.

GAME APPARATUS.

No. 819,530.

Specification of Letters Patent.

Patented May 1, 1906.

Application filed September 13, 1902. Serial No. 123,332.

To all whom it may concern:

Be it known that I, HERBERT A. FINNEY, a citizen of the United States, residing at Crum Lynne, in the county of Delaware, State of Pennsylvania, have invented certain new and useful Improvements in Game Apparatus; and I do hereby declare the following to be a full, clear, and exact description of the invention, such as will enable others skilled in the art to which it appertains to make and use the same.

This invention relates to game apparatus; and it has for its object the provision of a construction wherein instead of there being a separate dial for the index to show the moves the players are to make such moves will be indicated directly upon the face of the board over which the men are moved.

A further object of the invention is to provide a new arrangement of the parts of the game such as will give entertainment.

Other objects and advantages of the invention will be understood from the following description.

In the drawings forming a portion of this specification, and in which like numerals of reference indicate similar parts in the several views, Figure 1 is a plan view of a game apparatus involving the present invention. Fig. 2 is a transverse section through the apparatus and illustrating the mounting of the index.

Referring now to the drawings, there is shown a board 5, on which are marked four concentric spiral paths 6, 7, 8, and 9, the outer ends of which are spaced apart ninety degrees and the inner ends of which communicate with a central circular inclosure 10. The paths are marked with radial lines which separate the paths into spaces, each of which represents one mile, and at corresponding points of the several paths are marked the "penalties." The penalties are represented by the words "lost," "rest," "storm," "breakdown," "pass blocked." At the outer edge of the board and arranged in an annular series are numbers representing miles. At the center of the board is a post 11, on which is rotatably mounted an index 12, 50 which extends slightly beyond the paths, so as to designate the number of miles credited to each player.

It will be noted that the index 12 is at considerable elevation above the face of the board, so that it may pass readily over game-

pieces occupying any of the blocks of the paths.

Each player has a number of men, each group or party of men being the same color and different from the other groups or parties, and at the outer and inner ends of the paths are marked blocks 13, which are colored to correspond to the different parties.

In playing the game each player spins the index and each time the index stops at "10 miles" he may bring out one of his men and start him at the block at the outer end of his path. When the index stops at a number in the outer series, the player may advance one man the corresponding number of miles marked on his path. If, however, the index stops at "lost," then as many men as he has on his path are removed from the board, and if all of his men are on the path he is out of the game. The rules of play may of course be varied, and, if desired, when a man stops on a penalty he may be made to remain there until the player again makes ten, which was required to start him in the first instance.

A particular advantage of the present arrangement is that there is provided a means for determining who shall be the first player. This is done by spinning the indicator and the first play falls to him who has chosen the path nearest to the opening to which the arrow stops.

The several players are thus advanced successively along the several paths by the players, and the person who first gets his men into the central inclosure wins the game.

It will be understood that in practice modifications of the specific arrangement shown may be made and that any suitable materials and proportions may be used for the several parts without departing from the spirit of the invention.

What is claimed is—

A game-board having marked thereon a plurality of concentric spiral paths, each of said paths being divided into blocks for movement of game-pieces thereover, penalties indicated on said board exterior to said paths and numbers for indicating the movement of game-pieces over the said blocks, said numbers being disposed alternately with said penalties, the outermost ends of said paths being disposed at ninety degrees to each other and the inner ends of said paths terminating in the center of the center of the board at a point in a line with the opposite

ends thereof, there being a series of said paths located between the ends of each one of the four paths and an index pivoted concentric with the paths, the said index being spaced vertically from the said board to allow passage of the former over game-pieces on the latter.

In testimony whereof I affix my signature in presence of two witnesses.

HERBERT A. FINNEY.
